UNITED STATES PATENT OFFICE.

WILLIAM RANKIN, OF CHICAGO, ILLINOIS, ASSIGNOR OF ONE-THIRD TO
MATTHEW RANKIN, OF SAME PLACE.

PROPELLING MECHANISM FOR BOATS.

SPECIFICATION forming part of Letters Patent No. 625,059, dated May 16, 1899.

Application filed December 15, 1897. Serial No. 661,934. (No model.)

To all whom it may concern:

Be it known that I, WILLIAM RANKIN, of Chicago, in the county of Cook and State of Illinois, have invented certain new and useful Improvements in Propelling Mechanism for Boats, of which the following is a specification.

This invention relates to propelling mechanism for boats, and has for its object to provide a mechanism of this description whereby a boat may be readily and conveniently propelled by hand-power.

To this end my invention consists in certain novel features, which I will now proceed to describe and will then particularly point out in the claims.

In the accompanying drawings, Figure 1 represents a plan view of a boat having my improved propelling mechanism applied thereto. Fig. 2 is a side elevation of the same. Fig. 3 is a plan view of the propelling mechanism detached from the boat. Fig. 4 is a side elevation of the same, the propeller and rear portion of the propeller-shaft being omitted; and Fig. 5 is a transverse sectional view taken on the line 5 5 of Fig. 3.

In the said drawings I have shown my invention applied to the propulsion of a boat or launch A, it being adapted for the propulsion of boats of this general type and character.

B indicates a screw-propeller, which may be of any approved type and which is mounted on the end of a propeller-shaft C, which is itself mounted in bearings C' and C² within the boat. The rear bearing C' is located near the rear end of the shaft, while the front bearing C² is located near the front end thereof and mounted on or forming a part of a framework or support D, which carries a portion of the actuating mechanism. The bearings C' C² are preferably ball-bearing, as shown, for the purpose of reducing the friction and end thrust to a minimum. The shaft C is provided with a bevel-gear C³ on its front end within the frame D.

E indicates a transverse shaft mounted in the framing or support D and provided with a bevel-gear E', which meshes with the bevel-gear C³ on the shaft C, said shaft E being also provided with a pinion E², which meshes with a gear F on a second transverse shaft F', also

mounted in suitable bearings in the framing D. The shaft F' is provided with a fly-wheel F² for giving steadiness and continuity of motion and also has secured on it a crank-wheel F³, provided with a crank-pin F⁴, which is connected by a pitman G to a hand-lever H, fulcrumed at its lower end in a suitable bearing h and provided at its upper end with a suitable handle h', by means of which it may be vibrated. The boat A is provided with a seat A' adjacent to and in the rear of the lever H, whereby the operator, occupying said seat, may be in convenient reach of said lever.

It will be seen that when the lever H is vibrated or moved back and forward upon its fulcrum rotary motion will be imparted by the pitman G and crank-wheel F³ to the shaft F', and thence at an increased rate of speed to the shaft E, which latter in turn causes the propeller-shaft C to rotate at a still higher rate of speed. In practice I prefer to provide the shafts E and F' with ball-bearings e of any suitable construction—such, for instance, as that shown in detail in Fig. 3 of the drawings.

In order to provide continuity and smoothness of movement, I provide a spring-equalizing mechanism constructed in the following manner: One of the rotating parts, in this instance the fly-wheel F², is provided with an eccentric-pin I, which engages a block J, mounted to slide horizontally in a guideway or cross-head K. The block J is provided with projecting arms j, and on these arms, between said block and the respective ends of the cross-head K, are mounted springs J'. The cross-head K is in turn provided with two pairs of upward and downward extending guide-rods k, which pass through suitable apertured guide-plates or keepers L, mounted respectively at the top and bottom of a supporting-standard L'. K' represents springs mounted on the guide-rods k between the cross-head K and the guides or keepers L. It will be seen that as the shaft F' rotates the several springs J' K' are successively compressed and expanded, and by this operation they serve to give continuity and smoothness to the rotary motion of the shaft F'. As a further and auxiliary device for this purpose I

provide in connection with the lever H springs M, mounted on a suitable standard M' and having their free ends connected by links m to the lever H, these springs being each alternately contracted and expanded by the reciprocation of the lever and serving, further, to insure continuity and smoothness of movement and to carry the parts past the dead-point.

10 By means of the mechanism above described a boat may be conveniently and readily propelled by manual power at a high rate of speed with a minimum amount of exertion.

I do not wish to be understood as limiting myself strictly to the precise details of construction hereinbefore described, and shown in the drawings, as it is obvious that the structure may be modified without departing from the principle of my invention.

15 20 I claim—

1. A propelling mechanism for boats, comprising a propeller-shaft provided with a screw-propeller, a transverse shaft connected therewith by suitable gearing and provided

with a crank, a vibrating hand-lever connected with said crank by a pitman, an eccentric-pin connected with a rotating part on said shaft, and a vertically-reciprocating spring-controlled cross-head, provided with a horizontally-reciprocating spring-controlled block 30 therein with which said eccentric-pin engages, substantially as described.

2. A propelling mechanism for boats, comprising a longitudinal shaft provided with a screw-propeller, a transverse crank-shaft connected therewith by suitable gearing, compensating springs adapted to be alternately compressed and expanded by the rotation of said shaft, a vibrating hand-lever operatively connected with said crank-shaft, and compensating springs connected with said vibrating lever and adapted to be alternately compressed and expanded by the vibrations thereof, substantially as described.

35 WILLIAM RANKIN.
